[57] CLAIM

The ornamental design for an overhead, ergonomic scrub brush handle, as shown and described.

DESCRIPTION

FIG. 1 is a front, side and top perspective view of an overhead, ergonomic scrub brush handle showing our new design, with bristles shown in phantom lines; FIG. 2 is an enlarged top plan view thereof; FIG. 3 is a side elevational view thereof, both sides being identical;

FIG. 4 is a front elevational view thereof; FIG. 5 is a rear elevational view thereof; and FIG. 6 is a bottom plan view thereof.

The broken line showing of bristles in FIG. 1 is for illustrative purposes only, and forms no part of the claimed design.
